UNITED STATES PATENT OFFICE.

MOSES Y. RANSOM, OF CLEVELAND, OHIO.

DESIGN FOR A FOOT-STOOL.

SPECIFICATION forming part of Design No. 18,827, dated December 25, 1888.

Application filed November 5, 1888. Serial No. 290,021. Term of patent 3½ years.

To all whom it may concern: .

Be it known that I, MOSES Y. RANSOM, a citizen of the United States, residing at Cleveland, in the county of Cuyahoga and State of Ohio, have invented and produced a new and original Design for a Foot-Stool, of which the following is a specification, reference being had to the accompanying drawing, forming part thereof.

10 The figure is a side elevation.

The foot-stool is designed to grotesquely represent a pig. The body P is made of suitable material, and has a slot, I, at the end of the snout to represent the mouth. Pegs G 15 serve as legs, and a spiral peg, h, of graceful trend, suggests a tail. The ears o are of suit-

able fabrie, and a broad band, g, of fabrie, is fastened to the central portion of the body. After the manner of decorating household pets, a bow is shown embellishing the tail; but 20 the bow is not considered essential.

What I claim is—

A design for a foot-stool, the same being a conventional representation of a pig, as shown.

In testimony whereof I sign this specification, in the presence of two witnesses, this 11th day of September, 1888.

MOSES Y. RANSOM.

Witnesses:

CHAS. H. DORER,
ALBERT E. LYNCH.
